BARBECUE GRILL

A. Baker Barnhart, New York, N. Y., assignor to Modern Carpet Sweeper Co., Inc., Brooklyn,
N. Y., a corporation of New York

Application January 21, 1950, Serial No. 7,391

Term of patent 3½ years

(Cl. D81—10)

To all whom it may concern:

Be it known that I, A. Baker Barnhart, a citizen of the United States of America, and a resident of New York, in the county and State of New York, have invented a new, original, and ornamental Design for Barbecue Grill, of which the following is a specification, reference being had to the accompanying drawing, forming part thereof, in which—

Fig. 1 is a perspective view of a barbecue grill, embodying my new design.

Fig. 2 is a fragmentary side elevational view thereof with the supports broken away for convenience of illustration.

The opposite side of my barbecue grill is like the side shown and the rear is plain.

I claim:

The ornamental design for a barbecue grill, as shown and described.

A. BAKER BARNHART.
